ABSTRACT

An automatic web taking-up device has a core disposed at one side of the travelling web for taking up the web, a press roller disposed oppositely to the core at the other side of the web, and a travelling cutter disposed in series with the press roller at the side where the web is fed into the nip between the input press roller for cutting the web.

AUTOMATIC WEB TAKING-UP DEVICE

BACKGROUND OF THE INVENTION

1. Field of the Invention

This invention relates to an automatic web taking-up device for transferring the web from a filled core to a new core without stopping the travelling web.

2. Prior Art

Heretofore, there existed a turret type taking-up device having a sawtooth cutter 10 as shown in FIGS. 6 to 9. As shown in FIGS. 6 and 7, in order to transfer the web 12 from a filled core onto a new core without stopping the travelling web 12, the web taking-up device had a sawtooth cutter 10 rockably disposed around the fulcrum 16 adjacent the periphery of the new core 13 and a press roller 14 rockably disposed around the fulcrum 15 for contacting the upper portion of the new core 13. A compressed air injection tube 11 was disposed at the right side of the sawtooth cutter 10 so as to eject the air from the injection tube 11 in such a manner that the end of the web 12 cut by the sawtooth cutter 10 may wind on the new core 13. The travelling web 12 is cut by the sawtooth cutter 10 rocking around the fulcrum 16. The air is ejected from the injection tube 11 simultaneously with the cutting. The press roller 14 disposed over the new core is rocked around the fulcrum 15 immediately before cutting so as to press against the new core 13. The end of the cut web 12 is wound around the new core 13 in accordance with the movement of the air injection tube 11. Since the new core 13 is so rotated as to have the tangential speed in the same direction as the advancing direction of the web 12 immediately before the web is cut, it functions that the end of the web 12 tends to wind around the new core 13. As shown in FIG. 7, the compressed air injection tube 11 will be disposed at the right side of the sawtooth cutter 10 after rocking around the fulcrum 16 and is directed toward the nip A between the press roll 14 and the new core 13. Therefore, the cut web 12 is depressed by the air jet stream ejected from the compressed air injection tube 11 into the nip portion A. In this case, since the web 12 before being cut is travelling, the cut web 12 is not stopped, and the end of the cut web 12 is so rotated that the web 12 is nipped by the new core 13 and the press roll 14. The new core 13 has a tangential speed in the same direction as the advancing direction of the web 12 by the rotation of the shaft 18 and the end of the cut web 12 sometimes passes the nip portion A between the press roll 17 and the new core 13 with the result that the jet stream ejected from the compressed air injection tube 11 impinges upon the web at a point spaced from the end of the cut web 12 whereby it is wound as shown in FIG. 9. That is, the web 12 is folded into the nip A with the result that the end is wound up in the folded condition as shown in FIG. 10, so that the winding becomes irregular. If the winding becomes irregular when there is a photosensitive emulsion layer on the web, it causes a pressure fog. Since the travelling web is shock cut by the sawtooth cutter, the cut end portion is in sawtooth form. Also, this causes the production of wrinkles. When thin paper or plastic film is transferred automatically without stopping it by the conventional taking-up device having the sawtooth cutter and the compressed air injection tube, even if the paper or thin plastic film becomes folded or wrinkled at the initial period of the transfer, the folded or wrinkled portion is very small

with respect to the overall length and can be ignored. However, in the case of photographic film if the film becomes wrinkled or folded at some line by the winding, the loss of flatness of the film is a great disadvantage.

Thus, since the conventional device for conducting the method has many disadvantages, it is impossible to automatically transfer the web without stoppage of the web which is not preferable. Due to the irregularity of the surface of the core and to prevent scratches and defects in photographic film the web must be temporarily stopped to wind up the web on the core manually. For this reason, in order to prevent the device from temporarily stopping while the web is transferred, an accumulator for the web is sometimes provided immediately before the taking-up device.

SUMMARY OF THE INVENTION

This invention contemplates the elimination of the aforementioned disadvantages of the conventional taking-up device, and has as an object to provide a novel web taking-up device which transfers the travelling web from a filled core to new core without stopping it, subsequent to cleanly cutting the web, wrinkling or folding at the end of the cut web.

It is another object of this invention to provide a novel automatic web taking-up device which reliably transfers the travelling web without stopping the web with a simple mechanism.

It is a further object of this invention to provide a novel automatic web taking-up device which replaces the web from a filled core to new core without causing any scratch or other damage to the winding web.

According to one aspect of this invention, there is provided an automatic web taking-up device which has a core disposed at one side of the travelling web for taking up the web, a press roll disposed oppositely to the core on the other side of the web, and a travelling cutter disposed adjacent to the press roll at the side where the web is fed into the nip between the roller and the core for cutting the web.

Other objects, features and advantages of this invention will become apparent from the following description taken in conjunction with the accompanying drawings.

BRIEF DESCRIPTION OF THE DRAWINGS

FIG. 1 is a side view of the automatic web taking-up device in the state where the web is wound up according to this invention;

FIG. 2 is a side view of the automatic web taking-up device in the state immediately before the web is transferred from the filled core to a new core by the automatic web taking-up device of this invention;

FIG. 3 is a side view of the automatic web taking-up device of this invention in the state where the web is started to be transferred from the filled core to the new core;

FIG. 4 is a plan view in the direction shown by arrows a—a in FIG. 3;

FIG. 5 is a detailed partial perspective view of the web cutter which is an essential part of the automatic web taking-up device of this invention;

FIGS. 6 to 9 are side views of a prior art cutting and winding device using a sawtooth cutter, wherein FIG. 6 is a side view of the state of cutting and winding, FIG.

8 is a schematic view of the winding and FIG. 9 is an explanatory view of the state of winding; and

FIG. 10 is a side sectional view of the state of the web wound on the roll as a result of the method using the device of FIGS. 6-9.

DETAILED DESCRIPTION OF THE INVENTION

Reference is now made to the drawings, particularly to FIGS. 1 and 5 which show one embodiment of the automatic web taking-up device.

Reference numeral 1 illustrates a core taking up a web, 2 is a new core mounted to a turret type web taking-up device 9, 3 is a cutter support arm in the state when the web is taken up by the core 1 and 8 is a side-adhesive tape adhered to one end of the core 2 in this state. The turret 9 is rotated at the time when a predetermined length of web is taken up on the core 1 and at the same time the cutting and winding device on arm 3 approaches the core 2 so that it becomes ready for cutting and winding as shown in FIG. 2. In this case, it is desirable that the web does not contact the core 2 and press roll 4. Particularly, since scratches are great defects in the quality of material such as photographic film, it is a great advantage that in the ready state the web does not contact the core or press roller.

Subsequently, the press roller 4 presses the web 12' onto the core 2 after a "cutting and winding" signal is given and at the same time the cutter 6 travels along the guide rail 5 immediately upstream thereof as shown in FIGS. 3 and 4 so that the web is severed. The end of the cut web is introduced to the nip portion between the core and the press roller along the guide plate 7 where the end of the web is adhered to the double sided adhesive tape 8 by the nip pressure, and as shown in FIG. 4, the web is adhered onto the core. That is, the cutting and winding operations are conducted in parallel in sequence to each other from one side of the web to the other side with the result that the cutting operation across the width of the web is conducted without stopping the travelling web.

A sharp edge cutter is preferred so as not to produce irregularities in the travelling web. The cutter shown in FIG. 5 is suitable for cutting the travelling web 12' and may be reciprocated by any suitable means. The cutter is mounted for pivotal movement about the axis O-O' on a block which is mounted for reciprocating movement in a suitable groove on a cutter support arm 3. As a result, with this pivoted knife arrangement, the cutting angle of the knife will automatically vary with the

ratio of the feeding speed and the cutter speed.

In order to wind the web 12' onto the core without any fold or wrinkle of the end of the web, it is important to introduce the end of the web smoothly into the nip portion. For this purpose, it is effective to depress the end of the web by blowing lightly on the web from above with air so as not to separate the end of the web from the guide plate.

The function required for the double sided adhesive tape prepared previously on the core is to adhere the end of the web to the core. Accordingly, the adhesive tape is not necessary to wind the web around all the periphery of the core end, but may be small piece 8 as shown in FIG. 3. In this case, it is necessary to adjust the timing of the cutter travel so as to coincide with the adhesive tape at the nip portion between the core and the press roller at the edge of the web.

It should be understood from the foregoing description that since the automatic web taking-up device of the turret type is provided with the cutting and winding device of the present invention, it may clearly take up the web without folds and wrinkles without stopping the travelling web and without any scratches on the web. Thus it is possible to transfer the web from a filled core to new core with the present simple mechanism with safety.

What is claimed is:

1. An automatic web taking-up device comprising a core, means for mounting said core adjacent one side of a travelling web for taking up the web, pivoted support means disposed adjacent the opposite side of said web, a press roller mounted on said pivoted support means, means for moving said support means to press said web between said press roller and said core, travelling cutter means pivotally mounted on a reciprocable member on said pivoted support means adjacent to said press roller for movement transversely of said web on the upstream side of said roller relative to the direction of travel of said web between said core and said roller and adhesive means secured to said core for securing the leading edge of a cut web to said core for taking up the web.

2. An automatic web-taking-up device as set forth in claim 1 wherein said adhesive means is comprised of a double sided adhesive coated patch disposed adjacent the end of said core from which said traveling cutter means begins its traversing movement.
